UNITED STATES PATENT OFFICE

97,337

DESIGN FOR A SHOE

Francis Irving Sears, Webster, Mass., assignor to Bates Shoe Company, Webster, Mass., a corporation of Massachusetts

Application July 5, 1935, Serial No. 57,521

Term of patent 3½ years

To all whom it may concern:

Be it known that I, Francis Irving Sears, a citizen of the United States, residing at Webster, in the county of Worcester and Commonwealth of Massachusetts, have invented a new, original, and ornamental Design for a Shoe, of which the following is a specification, reference being had to the accompanying drawing, forming part thereof.

In said drawing, Fig. 1 is a plan view and Fig.
2 a side view of a shoe, showing my new design.

I claim,

The ornamental design for a shoe, as shown.

F. IRVING SEARS.
